CLASSIFICATION OF MATERIALS BY ELUTRIATION

Application filed September 8, 1930, Serial No. 480,549, and in Great Britain September 19, 1929.

This invention relates to the classification of solid materials, for instance sand and powdered material, of various kinds, comprising particles of solid matter of different sizes and 5 weights, by elutriation, according to the well known method of subjecting the material, in admixture with liquid, for example water, to the combined action of centrifugal force and 10 of gravity, whereby the different solid particles of matter in the material being treated, are separated from each other and fall at different rates in the liquid. Heretofore, a 15 common way of effecting the classification of material by the method referred to, has been to deliver the mixture of solid material and liquid into a vessel, usually and herein-after called a classifier, provided at its upper end with an overflow outlet for liquid carrying in suspension separated lighter and 20 smaller particles of the material (hereinafter called for brevity, fine particles) and at its lower end with a valve controlled outlet for regulating the discharge of separated heavier and larger particles of material 25 (hereinafter called for brevity, oversize particles) together with more or less liquid, the rate of overflow of the liquid carrying the fine particles, being dependent, to a large extent, upon the rate at which liquid with material to be treated is fed into the classifier, 30 and wherein a rotary motion is imparted to the mixture.

The present invention also has for its object to enable the proportion between the 35 quantities of liquid with admixed particles of matter discharged from the upper and lower ends of the classifier, and therefore the density of the respective streams, that is to say, the degree of fineness of the particles carried thereby, to be readily varied at will to suit varying requirements, without the use of a valve adapted to regulate the discharge of separate oversize particles from the lower outlet of the classifier during the 40 working of the classifier, though a shut-off may be provided for closing such outlet, when the apparatus is not in action, and for temporarily closing the outlet at starting.

The invention also has for its object to maintain the necessary degree of fluidity of

the oversize particles to ensure their proper discharge from the lower end of the classifier.

The classification of material by the elutriation method referred to, is effected, according to the present invention, by subjecting a mixture of the material and liquid to the combined action of centrifugal force and gravity within a classifier having free outlets at top and bottom and controlling the 55 rate of discharge of liquid with admixed particles through the upper and lower outlets by siphonic or suction effect produced on the liquid leaving the top of the classifier. The fluidity of the oversize particles required for 60 the effective discharge of such particles is maintained, when necessary, by automatic admixture of liquid therewith.

For enabling the improved method of classification to be carried out, the classifier used 70 therefor is, according to the present invention, provided at its upper portion with a suction producing device, preferably a siphon pipe, for drawing off liquid carrying fine particles, at its lower end with a discharge 75 pipe or spigot for the free discharge, during the working of the classifier, of oversize particles and liquid, and at an intermediate part of its height with an inlet through which liquid carrying the material to be classified can 80 be caused to enter in a tangential direction so that a rotary motion will be imparted to such liquid and material. The upper portion of the classifier is or may be provided internally 85 above the said inlet with annular conical passages for directing liquid carrying fine particles to the upper portion of the classifier and thence to the suction or siphon outlet, and the lower portion of the classifier is or may be provided with an inverted conical 90 annular passage leading to a central discharge outlet at the bottom and with which are associated means whereby liquid, it may be clear water, can be caused to flow into it at a suitable point in its height and flow upward, or partly upward and partly downward, according to the amount and degree 95 of density of oversize particles therein.

Classifiers such as described for enabling 100 the improved method of classification of ma-

terials by elutriation in the manner set forth to be carried out, can be constructed in various forms.

The accompanying illustrative drawing shows partly in vertical section and partly in elevation, one construction of classifier constructed and adapted to operate according to the invention.

According to the construction shown, the classifier comprises a casing having a cylindrical upper portion a provided with a central upper outlet b connected to a pipe c adapted to act as a siphon pipe, and a lower inverted conical portion a^1 connected to a central outlet pipe or spigot d , the cylindrical portion of the casing being also provided at a lower part thereof with an inlet e for the material to be classified, admitted through a tangentially arranged pipe e^1 . The outlet pipe or spigot d is provided with a hand operated valve d^1 , whereby it can be closed when the classifier is not in action and during the starting of the classifier, but is moved into a more or less open position when the classifier has been started, and is maintained in that position to admit of a continuous discharge of oversize particles from the said pipe or spigot d . Within the upper portion of the casing are preferably fixed two inverted hollow truncated co-axially arranged cones f and g of different internal and external diameters, the upper cone being preferably but not necessarily of greater depth than the lower cone. The upper cone is arranged to form a liquid tight joint with the upper part a of the casing and an inwardly and downwardly extending annular passage h with the lower cone g . The said upper cone f is preferably made of greater depth than the lower cone g and arranged to terminate near to a central stationary cone f^1 , but so as to leave a narrow opening between the two cones. The upper cone f is provided at an intermediate portion of its depth with annular rows of holes f^2 for a purpose hereinafter described. The upper end of the lower cone g is of such a diameter as to form between it and the casing, an annular passage i leading to the annular passage h between the two cones. Suspended centrally within the lower conical portion of the casing is a vessel k which forms with the lower conical portion a^1 of the casing, an annular space m of inverted conical shape in section, communicating directly with the lower central discharge pipe or spigot d . Means, as for instance, a central vertical pipe o , to which the aforesaid cone f^1 may be fixed, is provided for admitting liquid, for instance, clean water, to the said vessel, the lower portion of which is provided with an outlet that may conveniently be in the form of a circumferential outlet k^1 , through which liquid can pass from the vessel into the lower annular passage m . The said outlet is preferably formed between the lower

edge of the vessel k and a vertically adjustable plate k^2 so as to form an annular outlet k^1 of adjustable depth for the issuing liquid. a^2 is a window in the lower portion a' of the casing a^1 .

The operation of the classifier constructed as hereinbefore described is as follows:—

The material to be classified, mixed with water, is fed tangentially into the classifier, through the inlet pipe a' at a reasonably high velocity so that a rotary motion or vortex action will be imparted to the entire mass of mixture within the classifier. The first effect of this vortex action is to cause the particles to impinge against the inner side of the upper portion a of the wall of the classifier under the action of centrifugal force. The heavier particles will fall rapidly down the wall under the force of gravity and fall into the conical lower portion a' of the classifier and be discharged with more or less of the water through the lower discharge outlet d , while water and lighter particles will flow up the wall under the influence of the siphon action produced by the siphon pipe c . The effect of the vortex action is to produce a stress in the rotating mixture, causing a constant flow of mixture from the centre of the classifier to the outer periphery thereof. The upward flow of water, carrying fine particles and intermediate size particles in suspension, is directed upwards through the annular space i between the wall of the classifier and the lower cone g and thence downwards into the annular passage h between the two cones f and g . The greater portion of the water with the finest suspended particles therein, will pass, in the example shown, through the openings f^2 in the cone f into the space above that cone and be carried upwards through such space, as indicated by the arrows x , at a greatly reduced velocity to the outlet b and siphon pipe c , whereas the intermediate size particles will be projected downwards along the upper surface of the lower cone g and be thereby carried down to join the oversize particles. The downward movement of the intermediate size particles is also assisted by that portion of the stream of liquid flowing from the centre of the classifier below the cones, to the outer periphery thereof and thence through the annular space i and passage h , which does not pass through the perforations f^2 in the upper cone f . Water will continually circulate through the annular space between the upper portion a of the casing, a , a^1 , and the outer and lower cone g , the annular space i and the annular passage h , as indicated by the arrows y . The relative volumes of the water-solid mixture flowing upwards or downwards under the respective forces referred to, can be controlled by varying the suction effect at the upper outlet b by varying the weight of the liquid in the suction pipe c , as for instance by construct-

ing the siphon pipe c of such a length and diameter, and varying its effective length, that the whole of the water tends to flow upwards through the casing a a^1 to the upper outlet b thereof, or this upward flow can be reduced to any desired extent by suitably reducing the effective length of the siphon pipe, or by admitting air into the siphon pipe by an air valve c^1 , thereby reducing in each case, the weight of the contents of the siphon pipe and increasing the liquid pressure at the lower spigot outlet d , thus causing any desired quantity of the liquid to flow through the spigot outlet, such liquid carrying the oversize particles with it.

In the example now being described, the lower open end of the siphon pipe c , which is at a lower level than the spigot outlet d , is provided with holes c^1 and terminates a plate r to which is attached a discharge pipe s provided with a valve t . Carried by the plate r and surrounding the lower end portion of the siphon pipe c , is a cylindrical casing u that forms, with the said lower portion of the siphon pipe c , a chamber u^1 provided at its upper portion with an overflow outlet connected by a pipe v to the discharge pipe s below the valve t . The arrangement is such that by opening or closing the valve t to varying extents, water can be caused to enter the chamber u through the holes c^1 and be caused to rise therein to varying levels, which may be indicated by a gauge glass w , so as to admit of the effective length of the siphon pipe being varied to suit requirement.

It is well known that the velocity of flow of sand and water through an outlet of given area under a given pressure, depends upon the thickness of the film of water separating the particles of sand, or in other words, upon the fluidity of the mixture.

If particles of sand are allowed to settle into practically intimate contact with each other, the velocity is greatly reduced, and subsequently the weight of solid matter discharged in unit time is also much lower. The rate of discharge from a classifier provided at its lower end with an open spigot, is thus liable to be inversely proportional to the depth of the sand level above the spigot outlet. The result is, the greater the quantity of sand in the classifier, the slower will be its discharge, which, obviously, is the reverse of the condition required for practical working.

The original control of the discharge of liquid from the classifier can however according to the present invention, be adjusted so that the quantity of liquid discharging from the spigot outlet d is at all times in excess of that necessary to maintain fluidity of the mixture of liquid and oversize particles, in which case a high rate of discharge will be maintained, and no seal will be formed by the said particles. Under such conditions, the rate of discharge of liquid and oversize particles will

tend to increase with an increasing quantity of oversize particles, due to the increased weight of the mixture in the classifier over that in the siphon pipe. The effect of maintaining the fluidity of the mixture of liquid and oversize particles in this manner, is however, to allow a considerable quantity of fine particles suspended in the liquid to be carried down with the oversize particles, which may be a detrimental condition where a discharge of oversize particles only is required.

The aforesaid vessel k is provided to maintain the fluidity of the mixture of liquid and oversize particles, and consequently a rate of discharge increasing with the depth of the oversize particles, without allowing fine particles to be discharged with such oversize particles.

This result is obtained as follows:—

Adjustment of the siphonic action of the pipe c is made so that the rate of discharge of liquid and oversize particles through the spigot outlet d is slightly less than the rate at which oversize particles are fed into the classifier, with the result that a gradually increasing depth of oversize particles is formed in the lower annular passage m of the classifier. It is obvious that the whole of the clear water admitted to the aforesaid vessel k will flow freely through the circumferential outlet k^1 in the vessel. Owing to the fact that there is a gradual decrease of pressure below atmospheric pressure from the bottom to the top of the classifier, due to the siphon action described, the whole, or practically the whole, of the clear water issuing from the vessel k , acting as teetering water, will flow upwards and this will continue until the oversize particles have accumulated to such a depth above the outlet k^1 , as appreciably to resist the upward flow, when a portion of the issuing teetering water will be directed downwards, thus increasing the fluidity of the oversize particles flowing towards and through the spigot outlet d and thereby increasing the rate of discharge of the said particles and tending to lower or reduce the depth of the bed of oversize particles in the lower part of the classifier. By the means described, it is found by experiment that the bed of oversize particles maintains a practically constant level independent of the rate at which the oversize particles is fed into the classifier. A portion of the water issuing from the vessel k flows upwards the whole time maintaining a loose formation throughout the entire bed of oversize particles and also checking the descent of fine particles with the oversize particles.

The necessary velocity required to maintain the vortex action of the mixture of liquid and material within casing a , a^1 of the classifier can be produced by means of a pump 1, for instance a centrifugal pump, drawing its supply from a feed hopper 2. Or, alternately, the mixture of liquid and material may be

supplied under a head sufficient to impart, by mere gravity, the necessary velocity to the mixture entering the classifier.

What I claim is:—

- 5 1. For the classification of material by elutriation, a classifier comprising a casing having upper and lower outlets, suction means connected to the upper outlet of said casing and adapted to draw off liquid carrying fine particles of separated material, a discharge pipe connected to the lower outlet of said casing and adapted to admit of the free discharge of separated oversize particles of material and liquid, means adapted to discharge 10 into said casing between its upper and lower outlets and in a tangential direction, a mixture of liquid and material to be classified, and cones arranged within said casing above the inlet for mixed liquid and material and adapted 15 to direct liquid carrying separated particles to the upper outlet of said casing.
2. A classifier according to claim 1, wherein the said cones are inverted cones arranged concentrically one above the other and spaced 20 apart to form between them a downwardly and inwardly inclined annular passage open at its lower end and in communication through the upper portion of said casing with the upper outlet thereof, the outer periphery 25 of the lower cone being arranged to form an annular outlet passage between it and the adjacent portion of said casing, and the upper cone being connected at its outer periphery to said casing.
3. A classifier according to claim 1, wherein the said cones are inverted cones arranged concentrically one above the other and spaced apart to form between them a downwardly and inwardly inclined annular passage open 30 at its lower end and in communication through the upper portion of said casing, with the upper outlet thereof, the outer periphery of the lower cone being arranged to form an annular outlet passage between its 35 outer periphery and the adjacent portion of said casing and the upper cone being connected at its outer periphery to said casing and provided with outlet apertures between its upper and lower ends.
4. For the classification of material by elutriation, a classifier comprising a casing having free outlets at its upper and lower end and between such outlets a tangentially arranged inlet for mixed liquid and materials to be classified, a siphon pipe connected to the upper outlet, means for varying the weight of the column of mixed liquid and fine particles in said siphon pipe and means located within said casing between said upper outlet and 50 said inlet adapted to separate intermediate size particles from liquid flowing to said outlet and permit them to fall into the lower part of said casing.
5. For the classification of materials by elutriation, a classifier comprising a casing 55 having an upper cylindrical portion and a lower inverted conical portion, said upper portion being provided with a central outlet at the top and with a lateral inlet intermediate its upper and lower ends and said lower portion being provided with an outlet at the bottom, an external siphon pipe connected to the upper outlet, means for varying the weight of the column of mixed liquid and fine particles flowing through said siphon pipe, a pipe adapted to discharge a mixture of liquid and material to be classified, in a tangential direction through said inlet, a discharge pipe connected to the lower end of the portion of said casing and adapted to admit of free and continuous discharge of liquid and separated oversize particles therethrough, a valve whereby said discharge pipe can be closed when said classifier is not in use, a water vessel arranged centrally within the lower portion of the lower inverted conical portion of the classifier casing and having a circumferential outlet adapted to discharge water into a bed of oversize particles formed around said vessel and a pipe adapted to supply water to said water vessel.
6. Apparatus according to claim 5 wherein there are arranged in the upper portion of the classifier casing and above the inlet for mixed liquid and solid material two superposed inverted truncated cones and a central cone, the two superposed cones being arranged to form between them an annular downwardly and inwardly inclined passage open at top and bottom, the lower cone being arranged to form an annular outlet passage between itself and the wall of said casing and the upper cone being connected at its upper end to said wall and having its lower end terminating in proximity to said central cone, said upper cone having a plurality of outlet apertures therein intermediate its upper and lower ends.
7. For the classification of material by elutriation, a classifier comprising a casing having an upper portion with a central free outlet at the top and a lower inverted conical portion having a central free outlet at the bottom, an external downwardly extending siphon pipe connected to the upper outlet of said casing and adapted to draw off liquid carrying fine particles of separated material, means for varying the weight of the column of the mixture in said siphon pipe, a discharge pipe connected to the lower outlet of said casing and adapted to admit of the free and continuous discharge of separated oversize particles of material and liquid, means adapted to discharge into said casing between its upper and lower outlets, and in a tangential direction, a mixture of liquid and material to be classified, and means for introducing liquid into the lower portion of said classifier, said means comprising a vessel arranged centrally within the lower portion of the

classifier and adapted to admit of liquid issuing circumferentially therefrom and mixing with the surrounding bed of oversize particles and means for supplying liquid to said vessel.

5 Signed at London, England this 29th day of August, 1980.
